UNITED STATES PATENT OFFICE.

WILLIAM H. BALLINGER, OF COVINGTON, KENTUCKY.

KNIFE.

1,315,901.

Specification of Letters Patent. Patented Sept. 9, 1919.

Application filed June 2, 1917, Serial No. 172,457. Renewed July 3, 1919. Serial No. 308,534.

To all whom it may concern:

Be it known that I, WILLIAM H. BALLINGER, a citizen of the United States, residing at Covington, in the county of Kenton and State of Kentucky, have invented new and useful Improvements in Knives, of which the following is a specification.

This invention relates to a pocket knife wherein one of the blades is so constructed 10 that it may be employed for scribing lines upon timbers for use in the construction of frames for houses, boats, and the like.

The primary object of the invention is to provide a knife with a blade for this purpose 15 wherein through the operation of the spring pressed releasing pin, the blade will be caused to extend a considerable distance beyond one end of the handle by means of a spring arranged within the handle and associated with the blade, thus permitting the 20 blade to be moved to an active position more conveniently and with less effort than is the case with knives of this character now in use.

Another object of the invention is to provide the knife with a pin for the purpose 25 stated which also serves to retain the scribing blade within the knife handle when the scribing blade is not in use.

With these and other objects in view, the invention resides in the novel combination 30 and arrangement of parts, which will be hereinafter described and particularly pointed out in the claim.

The preferred embodiment of the invention has been illustrated in the accompanying drawing, although no restriction is necessarily made to the precise details of construction therein shown, as changes, alterations, and modifications, within the 35 scope of the claim may be resorted to when desired.

In the drawing:

Figure 1 is a perspective view of a knife 40 constructed in accordance with the invention, and showing one of the blades extending beyond an end of the handle to permit the blade to be employed for scribing lines upon timbers.

Fig. 2 is a longitudinal sectional view 45 through the knife, the scribing blade being shown retained within the knife handle by means of the releasing pin.

Fig. 3 is a vertical transverse section on 50 the line 3-3 of Fig. 2.

Fig. 4 is a detailed perspective view of one end of the scribing blade.

Like characters of reference denote corresponding parts throughout the several views in the drawing.

Referring now to the drawing in detail, the letter A designates a knife constructed in accordance with the invention and in which the handle 5 comprises spaced sides 6 60 between which are arranged a pair of frames 7 and 8 receiving therebetween, a parting strip 9, said strip having formed therein adjacent one of its ends a transversely extending slot 10.

Pivotedly connected with the handle 5 at 70 one end thereof is a blade 11 of the type commonly used in connection with pocket knives and adapted to fold within a channel 12 formed with the handle 5 by the frame 7, said frame being provided with a 75 resilient arm 13 for maintaining the blade 11 in extended position. The frame 7 has formed therein opposite the slot 10, a recess 14.

The frame 8 provides the handle 5 with 80 a longitudinally extending channel 15 into which adjacent the open end thereof extends a lug 16 on the frame, the other end of the channel being closed by a filler block 17 interposed between the parting strip 9 and one 85 of the sides of the handle, said filler block having formed thereon a stem 18 which extends longitudinally of the channel 15 for the greater portion of its length and is spaced from the sides of the frame 8 as 90 shown.

A second blade 19 which is coextensive in length with the channel 15 is mounted to slide therein and has extending longitudinally thereof for the greater portion of its 95 length, a slot 20 into which the stem 18 extends, said slot being enlarged for a portion of its length, as at 21, to receive therein a coiled expansion spring 22 which is mounted upon the stem 18 and has one end thereof 100 bearing against the filler block and its other end against shoulders 23 formed on the blade by the enlarged portion of the slot 20. The slot 20 is offset at one end, as at 24, with the offset portion registering with the 105 slot 10 and recess 14 when the blade 19 is in retracted position.

The blade 19 is recessed along one side edge for a portion of its length to provide the blade with a shoulder 25 to engage with 110

the lug 16 and limit the extent to which the blade may be extended beyond an end of the handle 5 by the spring 22. The blade 19 is notched, as at 26, to form at one end of 5 the blade, a hook 27, the bill of which has formed integral therewith along one side edge thereof, an extension 28 which is spaced from the side of the blade opposite the parting strip 9, said extension is curved trans- 10 versely throughout its length to extend toward the rear end of the blade and is provided at its lower edge with a cutting edge 29.

A spring pressed releasing pin for the 15 blade 19 is mounted to slide in the recess 14 in the frame 7 and has extending laterally therefrom between its ends a locking stud 31 which passes through the slot 10 in the parting strip 9 and the slot 20 in the blade 19, 20 said stud 31 being received when the blade 19 is in retracted position within the handle within the offset portion 24 of the slot 20, so that the stud through its engagement with the walls of the slot will prevent the spring 25 22 from moving the blade to an extended position until pressure has been applied to an operating head 32 on the pin to slide the same in the recess 14 in the frame 7.

When the blade 19 is in the position in the 30 handle shown in Fig. 2 in the drawing and it is desired to employ the knife as a scribing instrument, pressure is applied to the head 32 on the pin 30 to remove the stud 31 from the offset portion 24 of the slot 20, so that 35 the spring 22 may move the blade 19 longi-

tudinally of the channel 15 until the shoulder 25 on the blade engages the lug 16.

With the blade in this position, the knife may be manipulated to scribe the required line upon the timber to be cut and after 40 which the blade 19 may be forced within the handle 5 until the locking stud again engages a wall of the offset portion of the slot 20.

From the foregoing description, taken in 45 connection with the accompanying drawing, it is at once apparent that a knife has been provided wherein one of the blades may be employed as a scribing instrument when the occasion requires and the pin through the 50 operation of which the blade may be moved to an extended position by a spring for this purpose is so arranged and mounted within the handle of the knife as to prevent casual operation thereof to release the blade. 55

Having thus described the invention, what is claimed as new, is:

In a knife, a handle, a slidably mounted spring pressed pin projecting from the handle through one side thereof, a slidably mounted spring pressed plate in said handle having a longitudinally extending slot therein provided with an offset portion at one end, a partition in said handle passing between said pin and plate having a trans- 60 versely extending slot therein, and a stud on said pin extending through the said slot in the plate and the slot in said partition. 65

In testimony whereof I affix my signature. WILLIAM H. BALLINGER.

Copies of this patent may be obtained for five cents each, by addressing the "Commissioner of Patents, Washington, D. C."
